DESIGN FOR A DISPLAY REFRIGERATOR

Frank Maresca, New York, N. Y.

Application August 16, 1939, Serial No. 86,722

Term of patent 14 years

To all whom it may concern:

Be it known that I, Frank Maresca, a citizen of the United States and resident of the Borough of Bronx, county of Bronx, in the city and State of New York, have invented a new, original, and ornamental Design for a Display Refrigerator, of which the following is a specification, reference being had to the accompanying drawing, forming a part thereof.

The figure is a perspective view of a display refrigerator showing my new design.

I claim:

The ornamental design for a display refrigerator, substantially as shown.

FRANK MARESCA.
